UNITED STATES PATENT OFFICE.

GREGORY CALDWELL DAVISON, OF GROTON, CONNECTICUT.

SYSTEM OF AND APPARATUS FOR BAILING WELLS.

Application filed August 29, 1921. Serial No. 496,369.

To all whom it may concern:

Be it known that I, GREGORY C. DAVISON, a citizen of the United States, residing at Groton, in the county of New London and State of Connecticut, have invented certain new and useful Improvements in Systems of and Apparatus for Bailing Wells; and I do hereby declare the following to be a full, clear, and exact description of the invention, such as will enable others skilled in the art to which it appertains to make and use the same.

The method commonly used for raising oil from the bottom of oil wells is a plunger pump of small diameter with a piston packed by cup leathers or similar means, and ball check valves are used. The wells, which are pumped, vary in depth anywhere from a few hundred feet to over 4,000 feet. The result is that for wells of a thousand feet or over, the duty on the pump is very hard on account of the great lift and consequent high pressure. For instance, in a well a little over 2,000 feet, which is not at all uncommon, the pressure against which the pump works is 1,000 lbs. per square inch.

This condition of heavy pressure alone makes the duty on the pump very hard. But in addition to this there are two heavy handicaps. One of these is that a certain amount of gas collects with the oil and has a tendency to bind the pump for a considerable portion of the time. A second handicap, even worse, is the fact that loose sand gets into the pump, cuts the pump leathers, or other packing, scores the barrel and causes other derangement, which make it necessary to pull the pump plunger or tube from time to time. It is this pulling of tubing, etc., which constitutes one of the important expenses in the production of oil.

The invention hereinafter described is intended to overcome certain of the difficulties above enumerated, and is so arranged that all mechanisms are situated near the surface easily accessible.

According to my invention I use a bailing bucket which is lowered down into the well, and after becoming filled with the liquid to be removed therefrom the bucket is hoisted nearly to the top of the well, as will be hereinafter described, where it telescopes with a receiver located at the top of the well, and discharges the contents into said receiver; the liquid contents of the bucket flowing into said receiver and thence being carried

away to the receiving vats, or tanks, or other points of delivery.

In order to effect the economical operation of the device, the bailers are preferably operated in pairs, like two elevators, one going up as the other goes down, or vice versa.

The bailers which are lowered to the bottom of the well are always raised and the functioning takes place near the surface. In other words, what this system amounts to is the brazier which goes to the bottom of the well, brings up oil, and then the oil is forced out of the brazier by a pumping action at the surface, the whole operation being automatically operated, as will be hereinafter described.

My invention will be more fully understood after reference to the accompanying drawings in which like parts are indicated by similar reference symbols throughout the several views, and in which:

Figure 1 is a sectional view through two oil wells, showing a duplicate set of apparatus in which there are two bailers and two receivers connected together by a hoisting rope driven in reverse directions by a drum.

Figure 2 is a sectional view on a larger scale of the receiver enclosed in the well casing near the top thereof.

Figure 3 is a sectional elevation showing the bailing bucket used in connection with the receiver aforesaid.

Figure 4 shows a section along the line 4-4 of Fig. 3, and looking down.

Figure 5 shows an arrangement for operating the reversing switch for reversing the electric motor driving the drum shown in Fig. 1; and

Figure 6 is a diagram showing the electrical connections of the reversing switch shown in Fig. 5.

A represents the well casing which may be continued down any desired or preferred distance in the usual way. Surmounting this well casing is the casing head B from which the delivery pipe C leads. The casing head B is preferably constructed as shown in Fig. 2, in which it is shouldered, as at b', the screw threads b engaging the screw threads a on the exterior of the casing; the result being that a continuous inner cylindrical surface is secured at the joint between the casing and the casing head.

The casing head is also shouldered as at b² to support the cylindrical receiving cage D, which is perforated as at d² to register

with the opening through the delivery pipe C, and is screw threaded as at d to engage the corresponding screw threads e on the upper end of the oil receiving tube E, which 5 tube makes a tight joint with the flange d' and the lower portion of the receiving cage D. This receiving tube E has a plurality of openings e^o, preferably oppositely-disposed, which open directly into the annular 10 channel D^o of the receiving cage D. The upper end of the tube E is closed by the cap F, beneath which is the packing F', and this cap is secured to the casing head by means of the screws G.

15 H represents the hoisting cable which passes through a gland f at the upper end of the cap F, and is wound on the pulley I which is journaled on the shaft I', mounted on any suitable support, such as the 20 standards I² carried by the bracket B' secured to or integral with the casing head. The shaft I' should preferably be made readily detachable, so that the pulley may be quickly dismounted whenever desired. 25 The cable H goes from the pulley I to a suitable winding drum J, shown in Fig. 1. In this figure I have shown two entire sets of apparatus connected to a single winding drum, the advantage of which arrangement will be hereinafter more fully described.

The bottom of the receiving tube E is preferably formed of a casting E', screwed into the upper tube, and rounded outwardly 30 near its bottom, as at e', and provided with a wiper ring e², all as shown in Fig. 2. This casting E' is provided at its bottom with a spider, through the hub e³ of which the cable H passes. The openings in this 35 spider are closed by suitable lifting valves E² which may be pivoted at e⁴ and provided with suitable packing e⁵. One of the valves is shown in section closed in full lines, and lifted in dotted lines in Fig. 2.

40 The operation of these valves is substantially similar to that of the valves shown in Fig. 4, as will be hereinafter more fully described.

K represents the bailer (see Figs. 1 and 45 3) which is substantially cylindrical in form, and is preferably provided at its upper end with a flared-out portion k^o so as to be centered more readily over the rounded portion e' at the bottom of the receiving tube 50 E. This bailer is provided with suitable guides, preferably metal loops K' which guide and center the bailer in the well casing. The bottom of the bailer is provided with a heavy cap K² which is screw-threaded to 55 the cylindrical shell, as at k², and has the reinforced edges k³ at its bottom which form part of the spider, as shown in Fig. 3; the hub k of this spider being perforated to receive the end of the cable H which preferably passes through a washer L and is

held in place by a knob h as shown in Fig. 3. The openings through this spider are closed by lifting valves M which are pivoted as at m to the pivot collar N which forms a bearing for all of the several valves M, 70 as shown in Fig. 4. The pivot collar N is located on the upwardly projecting stem of the hub k and held in position by two lock nuts N' and N² which are threaded on to the uppermost end of the hub k. There 75 may be several of these collars, such as N' and N², the upper collars serving as lock nuts for the lower.

These valves M are provided with suitable packing m' held in place by the bolts m² 80 which screw up into the bosses m³. The construction and arrangement of these valves is shown in detail in Figs. 3 and 4.

It will be seen that when the bailer K is lowered into the well and strikes oil or other liquid therein, the valves M will be lifted and the liquid will flow into the bailer, and when the bailer is raised the valves will close of their own weight and remain closed, by the weight of the liquid 90 within the bailer. As the bailer is hoisted upwards toward the position shown to the right of Fig. 1, the flared portion k^o of the bailer will slip over the rounded portion e' of the receiving tube and the wiper ring e² 95 will serve both as a wiper ring and a packing ring, and the pressure on the surface of the liquid in the upwardly rising bailer will lift the valve E³ and will cause the bailer to empty its contents into the tube E, 100 from which it will overflow into the receiving cage D, and finally escape through the delivery pipe C.

It will be obvious that each round trip of the bailer will deliver a fresh supply of 105 liquid to the delivery tube and the process of bailing will be intermittently performed so long as the bailer is raised and lowered.

In order to render the system more economical as regards the amount of power required, I prefer to couple the bailers of two wells up in pairs so that the force exerted by one bailer and its cable in descending may be exerted to help hoist the other bailer 115 of the set in the well. This may be very readily accomplished by using a single winding drum, or a pair of winding drums on the same shaft operating in reverse directions and driving the same by any suitable reversible motor, such, for instance, as a 120 quick reversible electric motor. Such a system I have shown diagrammatically in Figs. 1, 5 and 6, in which P (see Fig. 1) represents an electric motor mounted on the shaft P', having the drum J on which the cables H 125 are wound, see Fig. 1. This motor may be reversed in any convenient way, either by hand or automatically as desired. Such a reversing switch is shown diagrammatically at Q in Figure 6. I prefer to reverse the 130

motor automatically, and to reverse the switch as each bailer rises to the upper limit of its travel as shown to the right of Fig. 1 and to the left of Fig. 5.

Such automatic reversing arrangement comprises a lever R pivoted as at r to the bracket R', projecting from the casing head B shown in Figs. 1, 2 and 5. There are two of these levers, as shown in Fig. 5, one end r' of each lever projects into the path of the bailer as it nears the limit of its upward travel, and the other end r² of each lever is connected to the wire or cable S which passes over the guide pulleys T, see Fig. 5, and is provided with collars t and t' adapted to engage the switch lever U, which makes contact in driving the motor in either direction through the contact pieces V and V'. The electric connections between the motor and the reversing switch are not shown, but such arrangements are well known in the art and are not a part of my present invention and will not be further described herein.

It will thus be noted that as each bailer attains the upward limit of its travel it will engage the corresponding lever and throw the reversing switch to the position for reversing the direction of the motor. This will cause the drum to rotate in the reverse direction, lowering the bailer that has just been emptied and lifting the opposite bailer which has just attained its lowest position.

I have shown the hoisting rope from two wells connected to a single winding drum which would be the proper arrangement where the two wells are of the same depth. Where one well is deeper than the other, in order that the system may be operated satisfactorily, it may be desirable to have a winding drum of greater diameter for the hoisting rope for the shallow well than would be the diameter of the drum for the hoisting rope for the deeper well. The drums could be very readily made of sizes to compensate for different depths of well. It will be seen that with the automatic construction hereinbefore described, the device will operate automatically as long as the electric motor is running.

It will be evident that the device may be applied to operate a single well only, in which case there would be no counterbalancing effect and the full power would be required in lifting the bailer; but the energy of the empty bailer and the parts connected thereto in descending may be made use of to generate electricity if desired, or to do other work. However, I prefer to couple up the bailers in pairs so that the descending unit, comprising the empty bailer and its cable, will assist in raising the full bailer and its cable. Thus a considerable saving in power may be effected.

The various parts should be made as light as consistent with the necessary wear, but

where the bailers are used in pairs the actual weight of the bailer itself is immaterial, since the descending bailer will counterbalance the rising bailer and the only difference in weight to be lifted will be the weight of the liquid contained in the bailer. It is true that there will be slight variations in the power required for lifting, incident to each operation, dependent upon the changing length of the cable as each bucket ascends or descends; but where the wells are of the same depth, and especially where a number of wells are operated in pairs as hereinbefore described from a central power station, these variations in power, owing to the differences in the length of the cable during the operation, will counterbalance each other.

While I have shown a single pair of bailers, it will be obvious that a large number of pairs may be operated from a central power station, dependent upon the conditions required.

It will be obvious that various modifications might be made in the herein described apparatus, and in the construction, combination and arrangement of parts which could be used without departing from the spirit of my invention; and I do not mean to limit the invention to such details except as particularly pointed out in the claims.

Having thus described my invention what I claim and desire to secure by Letters Patent of the United States is:—

1. Apparatus for bailing wells comprising a casing, a casing head mounted above said casing, a tubular receiver projecting into said casing head, a receiving cage provided with an annular chamber between said receiver and said casing head, and provided with a delivery outlet, a cylindrical bailer adapted to telescope over the bottom of said receiver, check valves opening upwards in the bottoms of said bailer and said receiver, respectively, resilient fenders in the form of loop spring secured to said bailer and separating it from engagement with the inner walls of the well, a hoisting cable passing through said casing head and said receiver and secured to said bailer, and means for hoisting and lowering said cable.

2. Apparatus for bailing wells comprising a casing, a casing head mounted above said casing, a tubular receiver projecting into said casing head and having a tapered bottom, a receiving cage provided with an annular chamber between said receiver and said casing head, and provided with a delivery outlet, a cylindrical bailer having a flaring mouth adapted to telescope over the bottom of said receiver, check valves opening upwards in the bottoms of said bailer and said receiver, respectively, resilient fenders in the form of loop springs secured to said bailer and separating it from

engagement with the inner walls of the well, a hoisting cable passing through said casing head and said receiver and secured to said bailer, and means for hoisting and lowering said cable.

3. Apparatus for bailing wells comprising a casing, a casing head mounted above said casing, a tubular receiver projecting into said casing head, a receiving cage provided with an annular chamber between said receiver and said casing head, and provided with a delivery outlet, a cylindrical bailer adapted to telescope over the bottom of said receiver, check valves opening upwards in the bottom of said bailer and said receiver, respectively, a hoisting cable passing through said casing head and axially through said receiver and also axially through said bailer, and secured to the bottom of said bailer, and means for hoisting and lowering said cable.

4. Apparatus for bailing wells comprising a casing, a casing head mounted above said casing, a receiving cage provided with an annular chamber between said receiver and said casing head, and provided with a delivery outlet, a tubular receiver projecting into said casing head and having a tapered bottom, a cylindrical bailer having a flaring mouth adapted to telescope over the bottom of said receiver, check valves opening upwards in the bottoms of said bailer and receiver, respectively, a hoisting cable passing through said casing head and axially through said receiver and also axially through said bailer, and secured to the bottom of said bailer, resilient fenders separating said bailer from the inner walls of the well, and means for hoisting and lowering said cable.

5. A system for bailing liquids from deep wells spaced apart and grouped in pairs, comprising a reciprocating bailer in each well, means for emptying said bailer as it arrives at the top of the well, a hoisting cable connected to each bailer of the pair, a winding drum for alternately hauling on the cable connected to one bailer, while lowering on the cable connected to the other bailer, and vice versa, whereby the weight of the descending bailer is caused to assist in the lifting of the ascending bailer, and a reversible electric motor for operating said winding drum, with means alternately operated by the movement of said bailer for automatically reversing said motor.

6. A system for bailing liquids from deep wells spaced apart and grouped in pairs, comprising a reciprocating bailer in each well, means for emptying said bailer as it arrives at the top of the well, a hoisting cable connected to each bailer of the pair, a winding drum for alternately hauling on the cable connected to one bailer, while lowering on the cable connected to the other bailer, and vice versa, whereby the weight of the descending bailer is caused to assist in the lifting of the ascending bailer, and a reversible electric motor for operating said winding drum, with means alternately operated by the movement of said bailer for automatically reversing said motor, said last mentioned means comprising a reversing switch for said motor, a lever at each well having an arm projecting in the path of the ascending bailer, and a flexible connection between said levers and said reversing switch.

GREGORY CALDWELL DAVISON.
